ALKYLATION PROCESS

Charles E. Hemminger, Westfield, N. J., assignor
to Standard Oil Development Company, a cor-
poration of Delaware

Application October 22, 1942, Serial No. 462,899

4 Claims. (Cl. 260—683.4)

1

The present invention relates to improvements in the art of the alkylation of olefins with isoparaffins and, more particularly, it relates to improvements in the process of producing an alkylate boiling within the gasoline range from an olefin and isobutane employing weaker sulfuric acid and higher temperatures than have heretofore been employed.

As is generally known, branch chain hydrocarbons boiling within the gasoline range and having an octane number of 100 or higher may be produced by reacting together an isoparaffin, such as isobutane, with an olefin, such as butylene in the presence of strong sulfuric acid, say acid of 95-100% strength, at temperatures of the order of about 35° F. It has been found that when the alkylation process previously indicated is carried out continuously that improvement in both quality and yield is maintained by maintaining in the reaction zone a relatively large molecular excess of isobutane over the olefin. For example, where at least 50 mols of the isoparaffin are present for each mol of the olefin in the alkylation zone good results are obtained in that the yields are improved and the quality of the product is improved over processes in which the molecular excess of the isoparaffin is substantially less.

I have now found that by employing C₃ and C₅ to C₇ olefins, as well as C₄ olefins and by operating at higher temperatures during the alkylation of the C₃ and C₅ to C₇ olefins, than customarily employed during C₄ olefin alkylation, I may employ sulfuric acid of 75-85 weight per cent and thereby effect considerable economy of operation, as regards acid consumption. For example, in the usual process of preparing an alkylate from isobutane and butylene employing strong sulfuric acid of say 98%, and withdrawing acid at 92% strength, the acid consumption is of the order of 1.2 lbs. of acid per gallon of alkylate produced. I have found that I may reduce this acid consumption to 0.8 lb. of acid of 85% strength per gallon of alkylate produced. I have also found that by decreasing the external ratio of isoparaffin to olefin to within the range of from 2-4 mols of isoparaffin per mol of olefin, I may also increase the production of the alkylate per volume of isobutane which is usually the critical material for alkylation. Thus, I may reduce the isobutane requirement from 1.15 gallons of isobutane to about 1 gallon of isobutane by my improved process.

I have further found that the most desirable method of operating my present process is to em-

ploy as a feed stock a cut or fraction say from a catalytic cracking operation containing C₃, C₄, C₅, C₆, and C₇ hydrocarbons. According to my preferred procedure, the C₄ hydrocarbons are alkylated under the usual alkylation conditions, that is, employing strong acid (over 92%). The C₃ hydrocarbons and the lower boiling portion of the C₅ hydrocarbons are then alkylated with the spent butene alkylation acid until its concentration is reduced to about 80 to 90%, 85% preferred weight per cent. The balance of the C₅, C₆, and C₇ hydrocarbons are then alkylated with an acid of about 75% strength. This series of operation reduced the acid consumption per unit of final alkylate to about one-half of the amount previously employed, and also gives a greater yield of alkylates, since saturated products are obtained from the C₅, C₆, and C₇ olefins with the consumption of lesser amounts of isobutane than usual, the remainder being available for alkylation of the C₃ and C₄ olefins. The spent acid from the 75% strength alkylation of the heavy olefins may be used to pretreat the heavier olefins to remove the dienes so as to reduce the acid consumption in the alkylation step. This pretreating is preferably accomplished with acid diluted to 60-65% strength.

The main object of my present invention, therefore, is to devise a process for alkylation of a relatively wide range of olefinic hydrocarbons, that is from C₃ to C₇ olefins, in stages, employing the spent acid from one stage as the alkylation catalyst in another stage, thus reducing substantially the acid consumption and effecting appreciable economy.

Another object of this invention is to provide alkylation technique adapted to obtain the maximum amount of alkylate from a given amount of isobutane.

Other and further objects of my invention will appear from the following more detailed description and claims.

In the accompanying drawing, I have shown a flow plan which indicates diagrammatically a preferred method of carrying my invention into practical effect.

I shall now set forth a specific example of my invention, and refer to the drawing. It will be understood that the following details are purely for purposes of illustration and not to impose any limitation on my invention.

In reference to the drawing, the "lighter ends" of a cracked petroleum gas oil were introduced into the present system through line 1 and thence 55 discharged into a fractionating column 3 where

the cracked stock was fractionated as below indicated. The feed stock in line 1 contained C₃, C₄, C₅, C₆ and C₇ hydrocarbons and in the fractionating column the C₄ hydrocarbons containing butenes were taken off as a side stream through line 4 and then discharged along with isobutane present in the C₄ hydrocarbons and recycled isobutane fed through line 5 to line 4 into an alkylation reactor 7 where they were treated with sulfuric acid of from 92% to 95% at a temperature of 35-85° F. for a sufficient period of time to effect the desired conversion. The alkylation of the C₄ hydrocarbons was carried out in known manner with the usual recycling of unreacted isoparaffin to the reaction zone from a distillation zone, and the process was otherwise operated according to known methods. It will be understood that if there is insufficient isobutane in the feed in line 1, additional isobutane may be fed from some outside source to the system through line 6. I have shown a settling drum 8 and a raw alkylate draw-off pipe 10, as well as an acid draw-off line 12. The raw alkylate in line 10 was delivered to a fractionator 15 where it was freed from isobutane, removed through line 18 and recycled through lines 5 and 11 to reactor 7, and thence discharged into a second fractionator 25 from which normal butane was removed through line 21. The raw alkylate was withdrawn through line 29. It will be understood that the product withdrawn through line 29 was delivered to conventional neutralizing, washing and distillation equipment to produce a finished alkylate in apparatus not shown. The spent acid in line 12 was in part recycled to the alkylation zone 1, but another portion of the spent acid was withdrawn through line 14. As is conventional, fresh acid was discharged from line 16 into line 12 to fortify the acid re-entering alkylation zone 1.

The acid in line 14 had a strength of about 85-90% by weight, and this acid was employed to alkylate the C₃ and the lighter part of the C₅ fraction. In other words, from tower 3, the C₃ hydrocarbons were taken off through line 20 and mixed with a fraction withdrawn through line 22, the latter cut containing the lighter ends of the C₅ hydrocarbons. The combined fractions were then delivered to a second alkylation zone 30 where they were alkylated in the presence of the spent acid in line 14 which was discharged into the alkylation zone 30 as shown. In alkylation zone 30 the temperature was maintained in the range of from about 45° F. to 100° F. Here, the ratio of acid to total hydrocarbon was from 100 to 500, and the external ratio of isoparaffin to olefin was from 3 to 6 isoparaffin per mol of olefin. The isoparaffin in this case was supplied from extraneous sources and was introduced into line 20 through line 21. However, some of the isobutane in line 5 may be withdrawn through line 19 and discharged into line 20 entering the reaction zone 30. The alkylation product was withdrawn through line 32 and discharged into a settling drum 34. The raw alkylate was withdrawn through line 36 and delivered to fractionators 15 and 25 through line 37 to recover isobutane for recycling to the system. The acid, on the other hand, was withdrawn through line 38 and recycled in part to line 14 entering alkylation zone 30. However, a major portion of this acid, which has a concentration of about 85% by weight, was withdrawn through line 40 and mixed with bottoms withdrawn from column 3 through line 42 in a manner which will be pres-

ently described more fully. The bottoms from line 42 contained that portion of the C₅ cut not withdrawn through line 22, together with the C₆ and C₇ hydrocarbons and these were discharged into an alkylation zone 43 along with extraneous isobutane through line 44 and/or isobutane withdrawn from line 5 through line 9 where they were admixed with the acid discharged therein through line 40. The temperature conditions prevailing in alkylation zone 43 were from 50° to 110° F.; the ratio of hydrocarbon to acid was about 2-5 parts by weight of hydrocarbon (total) per part of acid; and under these conditions an alkylation product was formed which was withdrawn eventually through line 50 and discharged into a settling zone 52 from which the separated raw alkylate was withdrawn through line 55 and delivered, first to fractionators 15 and 25 and then delivered to finishing equipment to recover the desired product. The spent acid, on the other hand, which had a strength of about 75% by weight, was withdrawn from settling zone 52 through line 60. This acid may be employed after dilution to about 65% to treat the heavier olefins in line 42 to remove diolefins therefrom.

In reaction zone 43 and also in reaction zone 30, the ratio of isobutane to olefin entering the said reaction zones was preferably from 2-5 mols of isobutane per mol of olefin and not more than 6 mols of isobutane per mol of olefin. In both zones some paraffins were formed by olefin polymerization, accompanied by carbon schism and hydrogen transfer.

It will be understood that the specific example which I have set forth above is purely illustrative and numerous modifications of the invention may be made without departing from the spirit thereof. For example, I may employ some other alkylation catalyst than sulfuric acid, such as the oxides of phosphoric acid, or sulfuric acid containing boron fluoride, nickel sulfate or hydrochloric acid. Also, the feed stock may be a different composition than that previously indicated or from other sources such as thermal cracking or reforming petroleum cuts or cracking of gases.

To recapitulate, my invention resides in obtaining a greater amount of alkylate from a given amount of isobutane and involves converting at least some of the olefins available in a refinery, into saturated branched chain paraffins by polymerization and inter-polymerization of said olefins, accompanied by some alkylation with isobutane. The possibility of obtaining paraffins from olefins by polymerization accompanied by hydrogen transfer under the conditions described above, is an important feature of my invention, from the standpoint of increased yields. One of the main features of my invention resides in the concept of employing diluted acids in the combined polymerization and alkylation of olefins other than C₄ olefins, also higher temperatures to increase yields. In all stages, I employ lower isobutane to olefin ratios than normally employed in alkylating C₄ hydrocarbons. I am enabled thus, to increase the overall yield of desired product over that obtainable from alkylating merely the C₄ or C₅ olefinic hydrocarbons according to known procedure.

To illustrate the advantage of my invention: When 100 gallons of a mixture of olefins containing 20 gallons of C₃ olefins, 35 gallons C₄ olefins, 30 gallons C₅ olefins and 15 gallons C₆ and C₇ olefins are alkylated under the conventional

operating conditions for alkylating butylene, where 90% or stronger sulfuric acid is used, with 6:1 isobutane to olefin molal ratio (external) and temperatures of 35° F., about 120 gallons of isobutane are consumed. However, following the process steps described above, only about 90 gallons of isobutane are required. Of course, the yield of aviation alkylate is less, namely about 140 gallons of compound to 160 gallons when the larger amounts of isobutane are required. However, this yield is greater than if only the proportional part of olefins were alkylated under usual conditions, namely about 120 gallons. On the other hand, if the same quantity of isobutane were used, 120 gallons, and excess olefins were available, the usual case in refinery balances, the alkylate yield would be 185 gallons. Thus, with the same size alkylate plant 185 gallons rather than 160 gallons are produced from the same amount of isobutane by this invention. The quality of the alkylate I produce in blends of high quality aviation gasoline containing tetraethyl lead is of the same quality as where only the C₄ olefins are employed.

Many modifications of my invention will occur to those familiar with the art. I am aware that I may not claim alkylation broadly, but I claim:

1. A combined method of converting a hydrocarbon fraction containing C₃ to C₇ olefins into substantially saturated hydrocarbons boiling in the gasoline range comprising alkylating the C₄ olefins from the C₃ to C₇ fraction with isobutane in the presence of concentrated sulfuric acid of alkylation strength in a first stage and alkylating the C₃ and C₅ to C₇ olefins from this fraction with isobutane in the presence of sulfuric acid of alkylation strength less concentrated than said concentrated sulfuric acid at a temperature above 35° F. in a second stage and maintaining the external isoparaffin to olefin ratio lower in the second stage than in the first stage.

2. A continuous method for producing branch chain paraffin hydrocarbons which comprises fractionating a feedstock containing C₃ to C₇ olefinic hydrocarbons and isoparaffins into an overhead fraction containing C₃ hydrocarbons, a first side stream containing the C₄ hydrocarbons, a second side stream containing the C₅ hydrocarbons, and a bottoms fraction, combining the overhead fraction with the second side stream alkylating the C₄ hydrocarbons in the

presence of strong sulfuric acid, alkylating the combined overhead and second side stream fraction with the spent acid from the alkylation of the C₄ hydrocarbons and alkylating the bottoms fraction with the spent acid from the alkylation of the combined overhead and second side stream fraction, and maintaining the external isoparaffin to olefin ratio lower in each succeeding zone in the direction of flow of the acid than in the preceding zone.

3. A continuous method for producing branch chain paraffin hydrocarbons which comprises fractionating a feedstock containing C₃ to C₇ olefinic hydrocarbons and isoparaffins into an overhead fraction containing C₃ hydrocarbons, a first side stream containing the C₄ hydrocarbons, a second side stream containing C₅ hydrocarbons and a bottoms fraction, combining the overhead fraction with the second side stream fraction, alkylating the C₄ hydrocarbons in the presence of 92 to 95% sulfuric acid at a temperature between 35 and 35° F. with an external isoparaffin to olefin ratio of 6 to 1, and alkylating the combined overhead and second side stream fractions with sulfuric acid having a concentration between 80 and 90 at a temperature between 45 and 100° F., using an external isoparaffin to olefin ratio of between 3 and 6 to 1 and alkylating the bottoms fraction with a sulfuric acid having a concentration of about 75% at a temperature between 50 and 110° F., and using an external isoparaffin to olefin ratio between 2 and 4 to 1.

4. The method set forth in claim 2 in which the temperature in the several zones is progressively increased in accordance with the molecular weight of the olefins undergoing alkylation.
